(57) **CLAIM**

The ornamental design for a door panel grouping, as shown and described.

DESCRIPTION

FIG. 1 is a front elevational view of a door panel grouping. FIG. 2 is a perspective view thereof.

FIG. 3 is an enlarged cross sectional view taken along line 3—3 of FIG. 1; and,

FIG. 4 is an enlarged fragmented perspective view of the lower left side. The panel has been illustrated broken at varying locations for ease of illustration. The broken lines are for illustrative only and form no part of the claimed design.

1 Claim, 4 Drawing Sheets
